BURNER FOR LIQUID FUEL

Josef Spirig, Hard, near Bregenz, Vorarlberg,
Austria, assignor to Anton Hofstetter, Widnau,
Switzerland

Application January 20, 1936, Serial No. 59,942
In Austria January 22, 1935

3 Claims. (Cl. 158—53)

The invention relates to a burner for liquid fuel such as oil and the like comprising a vaporizer or gasifier externally heated by a combustible mixture. These burners are particularly suitable 5 for furnaces and stoves. Various constructions of such burners have already been proposed which, however, were open to various objections. In most of these known constructions there is provided a vaporizer device through the interior 10 of which extends a vertical oil pipe having a delivering opening which is located above grooves or recesses, provided in the burner. The vaporizer device is mounted on a supporting plate and between these two members outflow openings are 15 provided for the oil to be gasified in the vaporizer. In order to start such a burner the vaporizer must first be exteriorly heated by a readily burning substance such as alcohol. When then the oil supply is opened the oil falls in drops 20 onto the exteriorly heated vaporizer and is there gasified to a greater or smaller extent. The oil thus gasified escapes through the openings and is ignited near them, so that as the operation is continued the gas itself maintains the vaporizer 25 at the required temperature. Such arrangements are open to the objection, that for starting, another fuel is required than for ordinary operation and furthermore the oil is not completely vaporized. The oil being supplied to the 30 hottest part of the vaporizer, causes only the more volatile constituents of the oil to be gasified on coming into contact with these red hot parts of the vaporizer since owing to the construction of the latter just referred to the less 35 volatile constituents of the oil flow downwardly and there either form a residue or must be led off by special pipings.

Now the object of the present invention is to enable the burner to be started by means of the 40 same fuel, for instance fuel oil, that is used for ordinary operation and to secure the gasification of all the constituents of the fuel. For obtaining this result it is necessary that the fuel be not supplied first to the hotter parts of the vaporizer, but to the less heated parts. Subsequently the fuel reaches the hotter parts, and thereby completely gasifying the oil. Furthermore it is necessary to so arrange the supply of air that there is an ample air supply at the point 50 where the oil comes first into contact with the vaporizer, and that the air current flows from this point to the hotter parts of the vaporizer. According to the invention this result is secured by providing in a substantially horizontal burner 55 tube a substantially horizontal vaporizer pro-

vided at its front end with a fuel oil supply and with delivery openings for the gasified fuel oil while its rear end is closed and its bottom slopes downwardly and rearwardly. Preferably the vaporizer is constructed as a horizontal conical tube increasing rearwardly in diameter. Further details of the invention relate to the connection of the vaporizer with the burner tube, the delivery openings for the gasified fuel oil, the way of securing the burner to the furnace door and other 10 details to be more fully described later on.

The drawing illustrates by way of example a constructional form of the present burner for liquid fuel. Fig. 1 is a central longitudinal section of the burner, Fig. 2 is a side elevation of 15 the burner tube and the vaporizer. Fig. 3 is a front elevation of the burner and Fig. 4 is a rear elevation of the parts shown in Fig. 2.

As is seen from the drawing, the burner constructed according to the invention comprises an 20 outer cylindrical burner tube 1 having a flange 2 near the middle of its length. The inner surface of the burner tube is slightly conical the wall of the burner tube decreasing in thickness from its inner to its outer end. The outer part of the 25 burner tube 1 from the flange 2 to its front end is solid and has at its front end an inner annular space 5 formed by an inner member 4. In the rear of the flange 2 there are provided in the wall of the burner tube four longitudinal 30 slots 31 separated from each other by four segmental flanges 32, (see Figs. 2 and 4). Within the burner tube there is mounted a tubular vaporizer 6 connected by ribs 7 with the flanges 32 of the burner tube 1. In the constructional form 35 shown the flange 2, the member 4, the ribs 7, the vaporizer 6 and the rear cover 8 are made integral with the burner tube 1. The thickness of the wall of the vaporizer is the same throughout its 40 length and the vaporizer is conical in shape increasing in diameter from the front end to its rear end. Its inner surface is provided with longitudinal grooves 11 separated from each other by ribs 10.

The front end of the vaporizer is approximately in the same plane as the inner edge of the member 4 and is closed by a cap 12 provided with a central threaded opening into which is screwed the inner end of the fuel oil supply pipe 13. The latter is provided with a delivery nozzle 45 14 projecting into the vaporizer 6 while to its outer end a bent piece of tubing 15 is secured which is connected in turn by a tubing 16 and a piece of hose 18 to a suitable liquid fuel container. An oblong flange 20 is secured to the 55

tubing 16 by a nut 19 and carries two forwardly projecting guide pins 21 guided at their front edges in another oblong flange 22 passing through slots in the wall of the burner tube and axially 5 fixed in position by these slots. Two coiled springs 23 are placed on the guide pins 21 between the flanges 20 and 22 and force the flange 20 and thereby also the closing cap 12 connected thereto against the vaporizer 6. An extension 10 24, secured to the flange 2, is attached to a furnace door 25 which is adapted to be pushed into a furnace or stove. Thus only half of the burner projects into the interior of the furnace while the other half together with the hose connection 15 is outside the furnace. Preferably the usual furnace door is removed and the door 25 fitting the burner is mounted in position in place thereof, but the usual furnace door might be provided, if desired, with an opening for the burner to be 20 inserted thereinto.

For starting the burner constructed according to the present invention, liquid fuel is caused to flow into the vaporizer nozzle 14 and collects within the vaporizer 6 until its level reaches the 25 lowermost point of the front opening of the vaporizer and then flows out between the cap 12 and the front end of the vaporizer 6, there being provided suitable leakage passages between the two or the cap not properly fitting the front end 30 of the vaporizer as in the case when the two are made of unwrought casting. The liquid fuel thus escaping between the cap 12 and the vaporizer collects at the bottom of the burner tube 1 and moistens an asbestos wick 26 or the like, 35 which is put onto the bottom. The bottom of the burner tube sloping downwards and forwards, the liquid fuel collects in the front part of the burner tube, where and when the asbestos wick is sufficiently soaked with the liquid fuel, 40 it is ignited and burns readily since the air enters into the burner in the direction of the arrow 27. The fire is carried to the rear by the air and then passes upwards in the furnace or stove. Thereby the vaporizer is heated and the liquid

fuel contained therein begins to gasify. Then the escape of liquid fuel between the cap 12 and the vaporizer 6 ceases and only gasified fuel escapes therebetween. This being mixed with air, is ignited and heats the vaporizer. The rear end 5 of the vaporizer is highly heated while its front end remains comparatively cool. The fuel first reaching comparatively cool parts of the vaporizer comes into contact with the rear parts of the vaporizer only after having flowed through a 10 comparatively large distance and the vaporizer being moreover closed at its rear end, a complete gasification of all the constituents of the ignited fuel is secured. The object of the longitudinal slots 31 is to cause the gas to be ignited as soon 15 as possible, that is to say immediately after escaping from the cap 12 in order that the vaporizer may always be surrounded by flames. If the gas pressure within the vaporizer 6 becomes too high the cap 12 may be shifted forward over- 20 coming the pressure of the springs 23, whereby the delivery opening is increased. Thereby an automatic safety means against excessive pressure in the vaporizer 6 is provided.

What I claim is:

1. A burner for liquid fuel comprising a burner tube, a vaporizer disposed within said burner tube and spaced therefrom, said vaporizer having its rear end closed and having a resiliently urged cap bearing against its front end and means for 30 leading liquid fuel to said vaporizer.

2. A burner for liquid fuel comprising a burner tube, a vaporizer disposed within said burner tube and spaced therefrom, means for leading liquid fuel to said vaporizer, a cap loosely fitting 35 one end of said vaporizer and means urging said cap against said vaporizer.

3. A burner for liquid fuel comprising a burner tube, a vaporizer disposed within said burner tube and spaced therefrom, means for leading 40 liquid fuel to said vaporizer, a cap loosely fitting one end of said vaporizer and spring means urging said cap against said vaporizer.

JOSEF SPIRIG.
